UNITED STATES PATENT OFFICE.

EDWARD S. GEROW, OF CORDELIA, CALIFORNIA.

WAGON-JACK.

SPECIFICATION forming part of Letters Patent No. 236,154, dated January 4, 1881.

Application filed October 18, 1880. (No model.)

To all whom it may concern:

Be it known that I, EDWARD S. GEROW, of Cordelia, in the county of Solano and State of California, have invented certain new and useful Improvements in Wagon-Jacks; and I do hereby declare that the following is a full, clear, and exact description of the invention, which will enable others skilled in the art to which it appertains to make and use the same, reference being had to the accompanying drawings, which form a part of this specification.

Figure 1 is a perspective view, and Fig. 2 is a vertical sectional view.

Corresponding parts in both figures are denoted by like letters of reference.

This invention relates to wagon-jacks or lifting-jacks; and it consists in certain improvements in the construction of the same, which will be hereinafter more fully shown and specified.

In the drawings hereto annexed, A represents an upright or standard provided with two lateral arms, B C, provided at their outer ends with openings D for a vertically-sliding stem, E, provided at its upper end with a button, F.

The upper end of standard A is provided with a transverse slot, G, in which is pivoted a lever, H, the short arm of which, I, is connected by a twisted link, J, which passes through an opening, z, of bracket B, and connected with a plate, K, having a perforation or opening, L, for the standard or sliding stem E, which passes through the said opening L, as well as through the openings D in the arms B C of upright A.

The lower rear end of the upright A is provided with a hook, M, by which the long arm or handle of the lever H may be secured or retained in a lowered position, so as to maintain the stem E in a raised position when so adjusted.

From the foregoing description, taken in connection with the drawings hereto annexed, the operation and advantages of my invention will be readily understood.

After placing the wagon-jack in position, with the button F of stem E under the axle of the vehicle, the said stem being raised so as to permit such adjustment, the long arm of lever H is lowered, thus raising the link J and plate K, and with the latter the stem E, which is held thereto by frictional resistance. It will thus be seen that the end of the vehicle-axle may be raised or lifted to any height required for all practical purposes. To lower the stem E the lever H is released from the hook M and elevated, which causes the inner surface of the twisted link J to abut against the standard A, thereby raising the plate K, which action permits the stem E to slide by gravity through said plate.

The stem E, which may be made of any desired length, enables my improved jack to be applied to wagons of almost any size and height.

I am aware of the Patent No. 200,117, of February 5, 1878, and I do not claim the construction therein shown.

Having thus described my invention, I claim and desire to secure by Letters Patent of the United States—

In a lifting or wagon jack, the combination of the transversely-slotted standard A G, having perforated brackets B C, the lever H, 75 pivoted in the slot of the standard, and having the twisted link J, passing through opening z of bracket B and connected to the perforated plate K, the vertical stem E, sliding in the openings D D L of the brackets and plate, and the 80 hook M, the whole constructed and arranged to operate as shown and described.

In testimony that I claim the foregoing as my own I have hereto affixed my signature in presence of two witnesses.

EDWARD SEARLES GEROW.
